(57) **CLAIM**

The ornamental design for a portion of a floor nozzle for a vacuum cleaner, as shown and described.

DESCRIPTION

FIG. 1 is a top, front and right side perspective view of a portion of a floor nozzle for a vacuum cleaner showing my new design,

FIG. 2 is a front elevational view thereof,

FIG. 3 is a right side elevational view thereof, the left side being a mirror image thereof,

FIG. 4 is a top plan view thereof; and,

FIG. 5 is a rear elevational view thereof.

The broken line showing of the remainder of the floor nozzle for a vacuum cleaner is for illustrative purposes only and forms no part of the claimed design. Also, the underside of the portion of a floor nozzle for a vacuum cleaner forms no part of the claimed design.
